UNITED STATES PATENT OFFICE.

ADOLPH W. MACHLET, OF ELIZABETH, NEW JERSEY.

CASE-HARDENING APPARATUS.

1,013,190.

Specification of Letters Patent.

Patented Jan. 2, 1912.

Application filed May 17, 1906. Serial No. 317,315.

To all whom it may concern:

Be it known that I, ADOLPH W. MACHLET, a citizen of the United States, residing in Elizabeth, in the county of Union and State 5 of New Jersey, have invented certain new and useful Improvements in Case-Harden- 60 ing Apparatus, of which the following is a specification.

This invention relates to chemically treat- 10 ing articles while heated and especially to case-hardening steel or iron articles in bulk.

In my co-pending application No. 244,244, filed February 4, 1905, (Patent No. 822,460, dated June 5, 1906,) is set forth a manner 15 of case-hardening by inclosing articles in a retort, and both heating and rotating the retort while a current of carburizing gas circulates therethrough.

The objects of the present invention are to 20 simplify and reduce the cost of the apparatus and the operation, and to adapt the same for certain kinds of work.

According to the present invention, the articles are placed directly in the flame 25 chamber of an oven and heated directly by the flames, and then the flames are extinguished, and the oven is filled with carburizing gas, which cements the articles by means of their own retained heat; a gentle agita- 30 tion of the articles being maintained throughout the heating and carburizing operations. This agitation is preferably effected by means of a revolving barrel mounted within the oven and containing 35 one or more cylindrical rolling shells which hold the articles; both the barrel and the shells being open to permit free circulation of carburizing gas therethrough. The barrel is provided with a lid or closure, through 40 which the shells may be removed; and the oven preferably has a lid in the form of a removable top to afford access to the barrel. The walls of the oven are greatly thickened 45 for the purpose of retaining heat, thus de- laying the cooling of the articles sufficiently to enable them to be substantially cemented by their retained heat, or by the heat re- tained in the oven. The lid of the oven is provided with one or more capacious vents 50 for the escape of products of combustion during the heating of the articles, and these vents are provided with closures, whereby they may be closed during the subsequent carburizing operation; and the oven is also 55 provided with a constricted regulatable vent for controlling the flow of carburizing gas

through the oven. The carburizing gas is preferably introduced into the oven through the same pipe which feeds the burners; and means are provided for diluting the carbu- 60 rizing gas by means of an inert gas, such as ammonia.

Other objects, features and advantages will hereinafter appear.

In the accompanying drawings, Figure 1 65 is a vertical longitudinal section of an apparatus for case-hardening according to the present invention. Fig. 2 is a plan of a re- volving barrel or cage showing particularly the hinged closure of the barrel through 70 which the shells may be inserted and re- moved. Fig. 3 is an elevation of one end of the apparatus. Fig. 4 is a transverse sec- tion of the apparatus.

The oven comprises end walls 1, 2, side 75 walls 3, 4, bottom or base wall 5, and top wall or cover 6. These walls, which are made of refractory material, are greatly thickened in proportion to the capacity of the oven, so that they retain heat, thereby 80 to delay the cooling of the articles, and hence prolong the cementing operation until a substantial shell is formed upon the contained articles. The walls rest upon an iron base plate 7, supported upon legs 8. An 85 iron boxing 9 confines the side and end walls. The lid 6, which is very heavy and rests upon the top edges of the side and end walls, is lifted off when desired by means of chains 10, to give access to the interior of the oven. 90 In the lid 6 are provided capacious vents 11, which are open during the operation of heating the oven, and may be closed by conical plugs 12 during the subsequent fill- 95 ing of the oven with carburizing gas.

Gas or other fuel is supplied to the oven through a pipe 13 controlled by a valve 14; and air is supplied through a pipe 15 controlled by a valve 16; the air being prefer- 100 ably supplied under pressure. The mixed air and fuel are distributed by means of pipes 17, 18, 19 and 20, to burners 21 in the base of the oven. Preferably the burners are arranged in two series in the opposite walls 3, 4, so as to direct the flames along the 105 floor 5 of the oven. A thick plate 22 of either iron or refractory material may lie horizontally just above the burners, spaces being left at 23 around the edges of the screen for the passage of flames up into the 110 body of the oven, whereby the flames are caused to heat the walls of the oven very

hot, as well as articles contained therein. The screen also because of its great thickness serves as a reservoir of heat effective to prolong the carburizing operation.

- 5 Extending through the end walls 1 and 2 of the oven is a horizontal shaft 24, which is preferably made of substantial proportions, so as to avoid collapse while heated, and the shaft is preferably hollow as illustrated, so 10 as to reduce the weight that must be supported by the heated metal, without substantially weakening the shaft. Secured upon said shaft by means of hubs 25, are opposite heads 26, connected by bars 27 15 preferably four in number; the ends of the bars being upset and attached to the heads by means of bolts 28, thus forming a rigid structure. Hoops 29 are placed at intervals between the heads and supported upon the bars 27, thus forming an open work barrel or cage. A segment 29^a of each hoop is hinged upon a rod 30 extending along the barrel; and these hinged segments which form a closure are locked in closed positions 20 25 by means of slide bolts 31 passing through eyes 32 provided upon the hinges, and engaging alining eyes 33 provided upon the barrel heads.

Within the barrel are shown three cylindrical shells or canisters 34 adapted to roll upon the interior sides of the hoops 29 when the barrel is rotated; the shells always tending to find the bottom of the barrel, as will be understood by reference to Fig. 4. The 30 35 articles to be case-hardened are placed within the shells, the latter having coned ends 34^a, which, though open at 34^b for enabling gas to circulate freely therethrough, are still sufficiently closed to retain the articles, with 40 45 which each shell may be only partly filled. In order to insert or remove the shells, the lid 6 of the oven is lifted and swung aside, and the closure of the barrel is unbolted and swung up.

- 45 The shaft 24 is revolvably supported by means placed at the exterior of the oven where they are not injured by heat. The ends of the shaft 24 projects through enlarged holes 24^a in the walls 1 and 2. The 50 55 left hand end of the shaft at Fig. 1 turns upon a pair of trundles 35 carried upon brackets 36 secured to the casing 9 of the furnace. The other end of the shaft is provided with a collar 37 supported upon a pair of trundles 38, said collar having flanges 39 to engage said trundles, to prevent endwise displacement of the shaft. The gradual permanent elongation of the shaft due to 60 65 repeated heating and cooling thereof, is accommodated by permitting the trundles 35 to engage directly with the shaft itself, since this end of the shaft may freely slide endwise upon said trundles. The shaft is rotated by means of a worm wheel 40 cast upon the collar 37 and operated by a worm

41 secured upon a shaft 42, the latter having a sprocket wheel 43 connected by a chain 44 to any source of power.

In operation the lid 6 is lifted, the barrel hoop segments 29^a unbolted and raised, and the shells 34 removed, filled with articles and replaced. Then the segments 29^a are closed and locked by the bolts 31. The valves 14 and 16 are then opened and the mixture is ignited at the burners 21, whereupon the lid 6 is replaced, the products of combustion escaping through the vent or vents 11. The barrel is slowly rotated, so that the articles contained in the shells are kept in constant gentle agitation, whereby they may become 80 evenly heated. The head of the barrel may be formed with rings 45 to be engaged by the ends of the shells, so as to retain the latter. The heating proceeds until the articles reach a carburizing heat which is say above 85 red heat and below the melting point; at which time the walls of the oven as well as the screen 22 are heated to about the same temperature as the articles. Thereupon the valve 16 is closed to cut off the air and extinguish the flames at the burners, and the vents 11 are closed by the plugs 12; and gas may continue to flow in through the pipe 13 to immediately fill the oven and carburize the articles in the shells; this gas being of 95 any suitable quality, as coal gas or any other carburizing fluid. The rotation of the barrel is continued throughout the carburizing operation, so that the articles may be exposed all over to the atmosphere of gas and 100 hence evenly cemented.

Preferably a constricted vent pipe 46 is fitted in the lower part of one of the walls of the oven, so that the current of carburizing gas may pass slowly through the oven, 105 thus insuring the drawing off of the vitiated gas, and the renewal through the pipe 13 of fresh gas. This vent may be regulated by a valve 47. The gas escaping through this vent and igniting in the air shows its 110 condition by the color of its flame. The operator is hence enabled to control the condition and flow of the gaseous atmosphere in the oven by regulating either valve 47 or 115 14 or both. Owing to the thickness of the heated walls, the cooling of the metal articles is greatly delayed, and they are enabled to become cemented to a substantial depth by means of their own retained heat, or preferably by means of the heat retained 120 in the oven. After the articles cool to a certain extent, the chemical action of the gas thereon ceases; and they may then be removed from the oven or retort and immediately replaced by other articles, so that 125 the operation of heating may be repeated before the walls of the oven have lost a great amount of heat. In case the cementation does not proceed to a sufficient depth, they may be allowed to remain in the oven, 130

and the valve 16 may be opened to admit air, and the oven again heated as before by raising the articles to the carburizing point, whereupon the flames may be again extinguished and carburizing gas supplied to the oven, thus causing the cementation of the articles to proceed to a greater depth; and this operation may be repeated on the same articles until they have the required depth of cementation; the agitation thereof being continued throughout the repeated heating and carburizing operations.

Ammonia or other inert gas may be admitted through a pipe 48 which joins the pipe 17, and is provided with a valve 49, the latter being closed during the operation of heating the oven. The mixture of gas and ammonia may be controlled by said valve 49; or other means may be provided for securing a supply of diluted gas to the oven. It will be seen that not only the burning mixture, but also the carburizing gas, with or without its dilutant are admitted through the burners; but the carburizing gas either diluted or not may be otherwise introduced into the oven.

The invention is of great value in case-hardening ordinary wire nails, as well as other small articles. A case hardened nail possesses great advantage over the ordinary nail in that it has sufficient strength in proportion to its diameter. In other words the ordinary nail is too weak to stand the pounding necessary to make a hole in the wood of the diameter of the nail; but by case-hardening the nail this difficulty is overcome. The nails may be readily case-hardened in bulk by the herein described means.

40 Variations may be resorted to within the scope of the invention, and portions of my improvements may be used without others.

Having thus described my invention, I claim:

45 1. The combination of a closed heating receptacle, a barrel in said receptacle, and means at the exterior of the receptacle and connected to said barrel for revolving the same; said barrel comprising a pair of heads, a series of hoops between said heads, and bars connecting said heads and supporting said hoops, and canisters confined in said barrel to be tumbled thereby for the purpose specified.

55 2. The combination of a closed heating receptacle, a barrel contained in said receptacle, and means at the exterior of the receptacle and connected to said barrel for revolving the same; said barrel comprising a pair of heads, a series of hoops between said heads, and bars connecting said heads and supporting said hoops; each hoop having a section which is hinged to give access to the interior of the barrel.

65 3. The combination of a closed heating

receptacle, a barrel contained in said receptacle, means at the exterior of the receptacle and connected to said barrel for revolving the same; said barrel comprising a pair of heads, a series of hoops between 70 said heads, and bars connecting said heads and supporting said hoops; each hoop having a section which is hinged to give access to the interior of the barrel; and releasable means for locking the hoops in closed relation.

4. The combination with a closed heating receptacle, of a barrel contained in said receptacle, a shaft extending through the wall of said receptacle, and having supporting 80 means exterior to said receptacle, and means for rotating the shaft; said barrel comprising a pair of heads secured to the shaft, hoops between said heads, and bars connecting said heads and supporting said 85 hoops; a segment of each hoop extending between adjacent bars being hinged, the segment having eyes, and locking bolts passing through the eyes and releasably engaging eyes which are provided upon said 90 heads.

5. The combination of a closed metal-heating receptacle, a barrel mounted therein for rotation, and a shell to contain the articles to be heated, said shell lying within said barrel and constructed to roll upon the interior of the barrel when the latter is turned.

6. The combination of a closed metal-heating receptacle, a barrel mounted therein for rotation, and a shell to contain the articles to be heated, said shell lying within said barrel and constructed to roll upon the interior of the barrel when the latter is turned, both said barrel and said shell 100 being open to permit free circulation of gas 105 therethrough.

7. The combination of a closed metal-heating receptacle, means for supplying gas thereto, a barrel within said receptacle, 110 means at the exterior of said receptacle for supporting and turning said barrel, and a plurality of rolling shells contained in said barrel, both said barrel and said shells having openings for the circulation of gas there-through.

115 8. The combination of a closed metal-heating receptacle, means for supplying gas thereto, a barrel within said receptacle, means at the exterior of said receptacle for supporting and turning said barrel, and a plurality of rolling shells contained in said barrel, both said barrel and said shells having openings for the circulation of gas there-through; said barrel having an opening 120 through which said shells may be removed, and a closure for said opening.

9. The combination of a closed metal-heating receptacle, a shaft extending through opposite walls thereof, means at the exterior 125 of said receptacle for supporting and turn- 130

ing said shaft, a barrel mounted upon said shaft within said receptacle and comprising a pair of heads, hoops intervening between said heads and means supporting said 5 hoops, and a cylindrical shell within said barrel and constructed to roll upon said hoops when the barrel is rotated.

10. The combination of a closed metal-heating receptacle, a shaft extending through 10 opposite walls thereof, means at the exterior of said receptacle for supporting and turning said shaft, a barrel mounted upon said shaft within said receptacle and comprising a pair of heads, hoops intervening between 15 said heads and means supporting said hoops, and a cylindrical shell within said barrel and constructed to roll upon said hoops when the barrel is rotated, each of said hoops having a hinged section to permit removal 20 of said shell, and means being provided for locking said sections; said shell having openings at its ends for the free circulation of gas therethrough.

11. The combination of a closed heating 25 receptacle, a barrel mounted therein and having openings, means for supplying gas to said receptacle, and a cylindrical shell contained in said barrel and constructed to roll within the same, said shell having openings at its ends for the free circulation of 30 gas therethrough.

12. The combination of a closed heating receptacle, a barrel mounted therein and having openings, means for supplying gas 35 to said receptacle, and a cylindrical shell contained in said barrel and constructed to roll within the same, said shell having open coned ends.

13. The combination with a heating chamber, of a cylindrical shell within said heating chamber and said shell having open coned ends, means within the heating chamber for rolling said shell, and means for supplying gas to the heating chamber.

40 14. The combination with a closed metal-heating chamber provided with a restricted vent, and means for conducting carburizing gas thereto, of means contained within the chamber for effecting agitation of the metal 45 articles contained therein, and driving mechanism exterior to the chamber and connected to said agitating means.

15. The combination with a closed metal-heating chamber provided with a restricted 55 vent, and means for conducting gas thereto, of an open device within the chamber for containing the articles to be heated, and power-driven means extending from the exterior of the chamber and through the wall 60 thereof to said containing device, for effecting movement of the latter to agitate its contents.

16. The combination with a closed metal-heating chamber provided with a restricted 65 vent, and means for conducting gas thereto,

of an open shell within the chamber, and power-driven mechanism including a part extending through the wall of the chamber to said shell, for effecting slow movement thereof during the heating of the articles 75 contained therein.

17. The combination with a closed oven whose walls are formed of refractory material, of burners for mixed air and fuel in said oven, means for supplying the oven, 75 after the extinction of flames at the burners, with a gas capable of chemically acting upon the articles contained in the oven while they remain heated, and means for agitating the articles in the oven; the walls of the oven 80 having great thickness for retaining heat so as to maintain the heat of the articles during the action of the gas thereon.

18. The combination of a closed oven having thick walls of refractory material, a 85 series of burners in said oven, means for supplying mixed air and fuel to said burners, means for supplying to the oven, after extinction of flames at the burners, carburizing gas, and means for gently agitating 90 the articles within the oven; said oven provided with a capacious vent for the products of combustion, and with a closure for said vent.

19. The combination of a closed oven having walls of refractory material, said walls being thickened for the purpose of retaining heat, a series of burners in said oven, means for supplying a burning mixture to said burners, and means for passing a slow current of carburizing gas through the oven after extinction of the flames at the burners, and power-driven mechanism partly within 95 and partly without the oven, for agitating the articles therein.

20. The combination of a closed heating chamber in the form of an oven having thickened walls of refractory material, a series of burners in said oven for burning mixed air and fuel, means for supplying 100 iron-carburizing gas to said oven after the extinction of the flames at said burners, a device within said oven for holding the articles to be carburized, and mechanism for moving said holding device, to agitate the 115 articles therein; said holding device being open so as to permit circulation of carburizing gas therein.

21. The combination of a heating chamber in the form of an oven provided with thickened heat-retaining walls, means for creating flames in said oven and venting the products of combustion therefrom, means for supplying iron-carburizing gas to said oven after the extinction of the flames therein, an open shell mounted within the retort, for containing the articles to be case-hardened, and means including a part extending through the wall of the oven, for effecting slow rotation of said shell.

22. The combination of a heating chamber in the form of an oven having a lid, means for creating flames in said retort and then supplying carburizing gas thereto after the extinction of the flames, a barrel mounted in the oven and having openings for the circulation of gas therethrough; and means outside of the oven for both supporting and rotating the barrel.
23. The combination of a heating chamber in the form of an oven, means for creating flames in said oven and for causing the circulation of gas therethrough, after extinction of the flames, a barrel movably mounted in the oven and having openings for the circulation of gas therethrough, and an open rolling shell contained in said barrel for holding the articles to be heated; said oven provided with a lid.
24. The combination of an oven having a lid, means for creating flames in said oven and for causing the circulation of carburizing gas therethrough after extinction of the flames, a barrel mounted in the oven and having openings for the circulation of gas therethrough, an open rolling shell contained in said barrel for holding the articles to be heated, and means outside of the oven for supporting and rotating said barrel; the latter having an opening for the removal of said shell, and a closure for said opening; said oven provided with a capacious vent for the products of combustion; and with a closure for said vent.
25. The combination of an oven having a lid in the form of a removable top, the walls of said oven being thickened to retain heat, a series of burners for mixed air and fuel opening into said oven, a revolute open receiver mounted in said oven for holding the articles to be case-hardened or treated, a thick screen between said burners and said receiver, flame passages being left between the edges of the screen and the walls of the oven, and means for supplying gas to said oven after extinction of flames at said burners; the oven provided with a capacious vent for the products of combustion and with a closure for said vent, and also with a regulatable constricted vent for regulating the passage of gas through the oven.
26. The combination with an oven having means for retaining heat, of means for creating flames in said oven and causing them to play upon said heat-retaining means,
- means for causing articles in the oven to be heated uniformly throughout, means for extinguishing the flames in the oven, and means operable after their extinction, for subjecting the articles uniformly to the action of gas thereon.
27. An apparatus for carburizing iron or steel articles, comprising a heating chamber of refractory material having three separate supply pipes 13, 15 and 48 for air, fuel gas and carburizing gas respectively, and means for closing the air and fuel gas pipes and opening the carburizing gas pipe to the chamber, and agitating the articles.
28. A furnace in which is mounted a barrel revolute upon an axle projecting through the walls of the furnace and supported upon trundles outside of the furnace, said furnace having a removable cover provided with vent-holes having closures, and means for introducing either gas alone or gas mixed with air; said furnace provided with a regulatable constricted gas-vent.
29. A furnace in which is mounted a barrel revolute upon an axle projecting through the walls of the furnace and supported upon trundles outside of the furnace, said furnace having a removable cover provided with vent-holes having closures, and means for introducing either gas alone or gas mixed with air; said furnace provided with a regulatable constricted gas-vent, and having in its bottom a heat-bed below which are burners for the gas, said burners within the flame chamber of the furnace.
30. The combination with a heating chamber, of a barrel mounted therein for revolution and consisting of heads, tie-rods, hoops, a hollow shaft upon which the heads are mounted, and a canister within the barrel to contain the articles to be case-hardened.
31. The combination of a heating chamber having means for supplying thereto either fuel gas mixed with air or carburizing gas after the flames are extinguished, a device revolutely mounted in said heating chamber, the latter having a removable top, and a closable vent in said top for the products of combustion, and a regulatable constricted vent in the side wall of the chamber for the slow escape of carburizing gas.
